UNITED STATES PATENT OFFICE.

WILLIAM K. LIGGETT, OF COLUMBUS, OHIO, ASSIGNOR TO THE JEFFREY MANUFACTURING COMPANY, OF COLUMBUS, OHIO, A CORPORATION OF OHIO.

VIBRATING SCREEN.

1,171,058.

Specification of Letters Patent.

Patented Feb. 8, 1916.

Application filed May 8, 1912, Serial No. 695,853. Renewed July 2, 1915. Serial No. 37,783.

To all whom it may concern:

Be it known that I, WILLIAM K. LIGGETT, a citizen of the United States, residing at Columbus, in the county of Franklin and State of Ohio, have invented certain new and useful Improvements in Vibrating Screens, of which the following is a specification, reference being had therein to the accompanying drawing.

10 This invention relates to improvements in screening mechanisms and particularly to that class comprising those in which an inclined screen cloth, along the upper edge of which is fed the material to be screened, 15 is mechanically vibrated thereby facilitating the passage through the screen of all material of a size smaller than the mesh of the screen.

In the drawings I have illustrated my improved form of screen in combination with an improved form of feeding hopper. The present application, however, does not relate to the feeding mechanism, the claims to this being presented in a divisional application, Serial No. 718,882, filed by me September 6, 1912.

In the drawings Figure 1 is a side elevation of the screening apparatus. Fig. 2 is a longitudinal vertical sectional view 30 through the screening apparatus. Fig. 3 is a perspective view showing a spreader frame to be used in the screening apparatus when more than one screen is used. Fig. 4 is a front elevation with parts broken 35 away. Fig. 5 is a rear elevation. Fig. 6 is a fragmentary side elevation of the improved screen vibrating mechanism. Fig. 7 is a sectional view on the line 7—7 of Fig. 6 showing the screen vibrating cam. 40 Fig. 8 is a sectional view on the line 8—8 of Fig. 5 showing the screen supporting and cushioning device. Fig. 9 is a fragmentary longitudinal vertical sectional view showing in detail the hopper and its feeding 45 mechanism. Figs. 10, 11 and 12 are diagrammatic views of the screen vibrating mechanism in several different positions.

Referring to the drawings, the numeral 1 indicates in general the screen stretchers and their supports which, together with the vibrating device comprises the screening mechanism proper. The screens are mounted within a casing provided with suitable doors for easy access to the interior, this 55 casing being supported upon a structural

framework adapted to be secured to a suitable foundation. The casing comprises vertical side plates 2, the front 3 with its swinging door 4, the inclined bottom 5, the upper back 6 and the inclined top 7 which is provided with two large hinged inspection doors 8, 8. An open section is provided in the bottom of the casing at 9 through which the various grades of material after screening fall by gravity into the hoppers or chutes located below the level of the apparatus. The framework 10 supports the casing upon its foundation 10'.

The screen proper comprises a rectangular frame 11 mounted at its upper end upon a transverse rod 12 which in turn is spring supported upon the framework 10. The lower end of the frame 11 is provided with outstanding lugs 13 which are engaged by a supporting cable 14. For the purpose of supporting the cable 14 and providing a winding mechanism by which the lower end of the screen may be raised or lowered to obtain the best angle of operation for different character of materials, a transverse shaft 15 is mounted in the front portion of the casing and provided with a pawl and ratchet mechanism 16. The cable 14 is continuous and passes through the two holes 17 drilled diametrically through the shaft 15. A hand wheel 18 is attached to the end of the shaft 15 by means of which it is operated thereby raising or lowering the lower end of the screen, the ratchet device holding it in any desired position.

The screen frame 11 is provided at its lower end and along its sides with upstanding fingers 19 which hold the screen stretchers in position and prevent displacement during operation. Side pieces 20 are secured to the sides of the frame and prevent material from over-running the edges of the screen.

When more than two grades or sizes of material are desired, it is possible with my improved frame construction to easily place within the frame two or more screens. To properly separate the lower ends of the screen stretchers 21, 22 and 23, I insert at the lower end of the frame 11 a spreader shown in Fig. 3. This spreader comprises the side blocks 24, the transverse connecting bars 25, and the two aprons 26 and 27. The end pieces of the spreader are formed with two steps or surfaces of different heights

28 and 29. When the spreader is placed in the lower end of the frame, the lower screen stretcher 21 will abut against the ends of the stretcher and material falling through this screen will be diverted by the apron 26. The second screen stretcher 22 is placed upon the step 28 of the spreader and material falling through this screen, and failing to go through the screen held by the 5 stretcher 21, will be diverted between the two aprons 26 and 27. The upper screen stretcher 23 is placed upon the highest step 10 29 of the spreader and is supported at its lower end by the fingers 19 secured to the frame 11. Material falling through this screen and of a size too large to pass through the screen carried by the stretcher 22, is diverted between the apron 27 attached to the spreader and the apron 30 15 attached to the lower corner of the frame 11. With this arrangement by which the lower ends of the screens are separated allowing the passage of material between them, the various grades are diverted into the bins or 20 chutes A, B, C and D. The aprons are made in two thicknesses or folds so that they can straddle the upper edges 31 of the chutes or bins into which they guide the material. 25

30 Several figures in the drawings have shown three screen stretchers placed upon the screen supporting frame, but it is of course evident that a greater or less number of screening surfaces may be used, depending upon the number of grades into 35 which it is desired to separate the material being screened.

The transverse rod 12 upon which the upper end of the screen frame 11 is mounted 40 passes outward through openings in the sides 2 of the casing and is supported in blocks 32 which slide within vertically arranged guide brackets 33 attached to the upright casing supports 10. Vertically arranged coil springs 34 are placed within the brackets 33 and bear against the upper and lower sides of the blocks 32. This arrangement allows the upper end of the screen mechanism to receive a vertical floating or 45 spring cushioned motion, the tension of the springs being adjusted by set screws 35 passing through the ends of the brackets 33.

A transverse shaft 36 is mounted in journals 37 upon the upper face of the casing 50 and is driven by a pulley 38. Mounted upon this transverse shaft at each side of the casing are two eccentrics 39 carrying eccentric straps 40. The cross section of each eccentric and strap is arced as shown 55 in Fig. 7 to prevent the strap from running off the sides of the eccentric, the inner surface of the strap being babbittted at 41. A hole is drilled through the upper eccentric strap and a grease cup 42 tapped into the 60 hole to provide lubrication for the eccentric. 65

Blocks 43 are placed upon the ends of the rod 12 and are slidably mounted within two separable bumper blocks 44. Connecting the bumper blocks and the eccentric strap are two rods 45 which act as pitmen and also secure together the two halves of the eccentric straps 40. The lower ends of the rods 45 or pitmen are threaded and pass through the bumper blocks 44. Nuts 46 are placed upon the threaded portion of the rods 45 above and below the two bumper blocks. Coil springs 47 surround the rods 45 and are placed between the two blocks, extending into recesses 48 in the inner faces of the bumper blocks. These springs separate the two bumper blocks and press them resiliently against the limiting nuts or stops 46. Collars 49 are secured upon the ends of the rod 12 so as to prevent the bumper blocks from becoming displaced and slipping over the blocks 43 when the machine is in operation.

The rotation of the shaft 36 through the eccentric 39 causes the rapid reciprocation of the two pitmen 45. The pitmen in turn cause the bumper blocks to vibrate rapidly back and forth upon lines slightly inclined from the vertical. By adjusting the nuts 46 the bumper blocks may be spaced toward or away from the blocks 43 so that the bumper blocks will travel a shorter or a greater distance before coming in contact with the blocks 43. The tendency of the supporting springs 34 is to constantly hold the rod 12 at a central point. The reciprocating bumper blocks give the rod 12 a short up and down motion.

Considering the pitman at its lowest position, the upper bumper block will be in contact with the upper side of the block 43 having pressed it to its lowest limit. As the eccentric swings past the center, the pitman will be at its lowest limit as diagrammatically shown in Fig. 10. As the eccentric passes its center and carries the pitman in an upward direction, the lower of the two coil springs 34 forces the rod upward to its central point indicated diagrammatically by Fig. 11. The next step in the cycle is the further upward movement of the pitman in which the upper bumper block draws away from the block 43 and the lower bumper block is brought sharply up against and delivers a hammer blow to the lower edge of the block 43, this latter position being illustrated diagrammatically in Fig. 12. On the downward throw of the eccentric the reverse train of operations is performed. The shaft 36 revolving at considerable speed in this manner delivers a succession of sharp hammer blows to the upper end of the screen alternating from an upward to a downward direction.

By adjusting the nuts 46 outward or inward upon the rods 45, the spacing of the

bumper blocks will be varied thereby varying the distance through which they will travel before delivering their blows to the ends of the rod. This allows of a wide variation in adjustment adapting the machine to various degrees of vibration depending upon the quality of material being screened. By this adjustment it is evident that the nuts may be tightened down so that the bumper blocks will contact on both sides of the block 43 thereby eliminating the hammer blows and thus give the ends of the rod 12 the smooth up and down movement equal to the throw of the eccentric. On the other hand, the nuts may be run out upon the rods 45, the springs 47 forcing the bumper blocks outward against the bolts to a point where the distance between the inner faces of the bumper blocks and the block 43 will almost equal the entire throw of the eccentric. In this position the ends of the rod 12 will be barely moved, but will receive alternately upward and downward a light tapping communicating to the screen a gentle vibration adapted for the best screening of certain grades of material.

Mounted on the upper end of the casing is my improved hopper and feeding device comprising the chute 50 feeding into a trough 51 extending the entire width of the casing and provided at its lower portion with an inclined plate 52 of a flexible material such as sheet steel, and securely bolted along its rear edge to the casing. Co-acting with this inclined plate or feeder bottom is a vertically slideable gate 53 positioned at the front of the hopper and adapted to be raised or lowered by hand wheels 54. An upturned lip 55 is formed on the lower edge of the plate 52 and co-acts with the gate 53 to prevent the material from flowing out through the hopper except when the plate 53 is vibrated. A transverse angle piece 56 is riveted along the under side of the inclined plate 52 and has attached to it downward and forward extending arms 57. These arms rest upon or bear against pins or lugs 58 attached to the side pieces 20 of the screen frame 11. The forward extending parts of the arms 57 are curved in arcs about the rod 12 as a center so that when the lower end of the screen frame is raised or lowered, the upper end swinging about the shaft 12, the lugs 58 will bear at all times the same relation to the arms. The vertical vibration of the upper end of the screen frame is through the above described arrangement transmitted through the arms 57 to the inclined flexible plate 52, this rapid vibration causing material to flow downward over the plate in a steady stream, the amount depending upon the elevation of the gate 53. The vibration of this plate which is securely fastened to its rear edge to the casing is of a nature that cannot be obtained where the rear edge of

the plate or hopper bottom is hinged or pivotally mounted. On the upward travel of the screen frame the hopper bottom, instead of being swung upward as is the case of the pivoted bottoms, is bent upward in a slight arc, this being found to greatly facilitate the distribution of the material transverse the feeder plate and give superior results.

The mounting of the screen stretchers in the manner described makes it possible to easily adapt the machine for a variety of sizes as the screen stretchers may easily be taken out or additional ones put in depending upon the number of grades desired. This is accomplished by using the spreader or adapter shown in Fig. 3 which separates the screening surfaces in such a manner that individual troughs or chutes are provided for the space intermediate the screening surfaces without making any alteration in the apparatus itself.

The upper end of the screen is tapped or hammered alternately upward and downward in a vertical plane while the lower end of the screen is adjustably supported by flexible cables. This arrangement is found to give a most efficient screening action in that the particles of material, instead of taking long jumps over the screening surface, are caused to rapidly vibrate up and down in more nearly vertical lines giving greater efficiency for a given screening surface than is the case where the particles take longer jumps. Furthermore, the hammering action in a vertical plane causes the screening surface to jump away from the material on the downward throw and to be quickly forced into contact with the material on the upward stroke.

What I claim is:

1. In a screening apparatus, the combination with the frame, of the inclined screen, the flexible support for the lower end of the screen, and means for vibrating the upper end of the screen in a vertical plane by blows delivered alternately in an upward and downward direction.

2. In a screening apparatus, the combination with the frame, of the inclined screen, the vertically adjustable support for the lower end of the screen, and the means for vibrating the upper end of the screen in a vertical plane by hammer blows alternating in an upward and downward direction.

3. In a screening apparatus, the combination with the frame, of the inclined screen, the flexible support for the lower end of the screen, the floating support for the upper end of the screen, and means for vibrating the upper end of the screen by means of hammer blows delivered alternately in opposite directions.

4. In a screening apparatus, the combination with the frame, of the inclined screen,

- the vertically adjustable support for the lower end of the screen, the vertically floating support for the upper end of the screen, and the means for delivering hammer blows alternately in opposite directions to the upper end of the screen.
5. In a screening apparatus, the combination with the inclined screen, of the support for the lower end of the screen, the floating support for the upper end of the screen, and the means for delivering hammer blows to the upper end of the screen in alternate directions.
6. In a screening apparatus, the inclined screen, the flexible support for the lower end of the screen, the transverse rod carrying the upper end of the screen, the spring cushioned supports for the ends of the said rod, and means for delivering hammer blows to the said rod alternating from an upward to a downward direction.
7. In a screening apparatus, the combination with a frame, of an inclined screen, a support for the lower end of the screen, the transverse rod carrying the upper end of the screen, supports cushioning the transverse rod in both an upward and downward direction attached to the frame, and means for alternately hammering the ends of the rod in opposite directions.
8. In a screening apparatus, the combination with the frame, of the inclined screen, the flexible support for the lower end of the screen, the transverse rod carrying the upper end of the screen, the springs supported in the frame and adapted to cushion the ends of the rod in both vertical directions, and the eccentrically driven pitman co-acting with the ends of the rod to hammer the said rod alternately in an upward and downward direction.
9. In a screening apparatus, the combination with the frame, of the inclined screen, the flexible support for the lower end of the screen, the transverse rod carrying the upper end of the screen, the springs carried by the frame and adapted to cushion the ends of the rod in an upward and downward direction, and the eccentrically operated pitmen, the free ends of the said pitmen loosely embracing the ends of the rod and thereby alternately hammering the ends of the rod in opposite directions.
10. In a screening apparatus, the combination with the frame, of the inclined screen, the flexible support for the lower end of the screen, the springs carried by the frame to cushion the upper end of the screen in both vertical directions, and the reciprocating pitmen, the lower ends of the said pitmen adapted to co-act with the upper end of the screen and alternately hammer it in an upward and downward direction.
11. In a screening apparatus, the combination with the frame, of the inclined
- screen, a support for the lower end of the screen, the transverse rod supporting the upper end of the screen, the springs carried by the frame for supporting and cushioning the rod in both vertical directions, the reciprocating pitmen and the bumper blocks secured to the pitmen and loosely surrounding the ends of the rod.
12. In a screening apparatus, the combination with the frame, of the inclined screen, the support for the lower end of the screen, the transverse rod supporting the upper end of the screen, the reciprocating pitmen, and the bumper blocks secured to the pitmen, the said blocks loosely embracing the ends of the transverse rod.
13. In a screening apparatus, the combination with the frame, of the inclined screen, the support for the lower end of the screen, the transverse rod supporting the upper end of the screen, the springs secured to the frame and adapted to spring cushion the transverse rod in both vertical directions, the reciprocating pitmen, and the spring separated bumper blocks carried by the pitmen and embracing the ends of the rod, said blocks being adapted on reciprocation of the pitmen to hammer the ends of the rod alternately in opposite directions.
14. In a screening apparatus, the combination with the frame, of the inclined screen, the support for the lower end of the screen, the transverse rod secured to the upper end of the screen, the springs carried by the frame and adapted to support and cushion the ends of the rod in both vertical directions, the reciprocated pitmen, the bumper blocks secured to the pitmen, the bumper blocks being provided with openings to embrace the ends of the rod, and means for varying the size of the openings.
15. In a screening apparatus, the combination with the frame, of the inclined screen, the support for the lower end of the screen, the transverse rod supporting the upper end of the screen, the reciprocating pitmen, the blocks mounted on the ends of the rod, and the bumper blocks secured to the ends of the pitmen and loosely engaging the said blocks on the ends of the rod.
16. In a screening apparatus, the combination with the frame, of the inclined screen, the support for the lower end of the screen, the transverse rod supporting the upper end of the screen, the reciprocating pitmen, the blocks mounted on the ends of the rod and the bumper blocks secured to the ends of the pitmen, the said bumper blocks being provided with openings adapted to receive the blocks on the ends of the rods, the said openings having greater dimensions longitudinal of the pitmen than the blocks on the rod, substantially as and for the purpose set forth.

17. In a screening apparatus, the combination with the frame, of the inclined screen, the support for the lower end of the screen, the transverse rod supporting the upper 5 end of the screen, the reciprocating pitmen, the blocks mounted on the ends of the rod, the bumper blocks secured to the ends of the pitmen, the said bumper blocks being provided with openings adapted to receive 10 the blocks on the ends of the rod, said openings having greater dimensions longitudinal of the pitmen than the blocks on the rod, and means for varying the said longitudinal dimensions of the openings in the 15 bumper blocks, substantially as and for the purpose set forth.
18. The combination in a screening apparatus, with a vibrated screen supporting frame, of the plurality of screen stretchers, 20 and the detachable spreader adapted to be placed within the screen supporting frame and separate the lower ends of the screen stretchers, substantially as and for the purpose set forth.
- 25 19. The combination in a screening apparatus, with the vibrated screen support-
- ing frame, of the plurality of screen stretchers, the spreader frame detachably mounted within the vibrated frame and adapted to support and separate the lower ends of 30 the screen stretchers and the aprons attached to the said spreader frame and adapted to divert material separated by the said screens.
20. In a screening apparatus, the combination with the vibrated screen supporting frame, of the plurality of screen stretchers, the upstanding finger pieces extending from the sides of the said frame, and the spreader frame resting upon the lower end of the vibrated frame and secured from displacement by the upstanding fingers, said spreader frame adapted to separate the lower ends of the screen stretchers placed 40 within the vibrated frame. 45
- In testimony whereof I affix my signature, in presence of two witnesses.
